ATTORNEY 3

UNITED STATES PATENT OFFICE.

GEORGE P. JACKSON, OF FLUSHING, NEW YORK, ASSIGNOR TO COMBUSTION ENGINEERING CORPORATION, OF NEW YORK, N. Y., A CORPORATION OF NEW YORK.

BRICK-ANCHORING MEMBER.

Application filed October 3, 1924. Serial No. 741,304.

My invention relates to anchoring members and especially to anchoring members for furnace walls. The invention may also be found applicable to other structures in which 5 the advantages hereinafter pointed out would be useful.

The nature, objects, and advantages of my invention will be best understood from a description of the invention as applied to a 10 hollow wall construction of a pulverized fuel burning furnace, for which, because of the expansion and contraction conditions, the invention is particularly adapted.

In the drawings, Fig. 1 is a face view 15 of my anchor device, the supporting girder and recessed brick being shown in dotted lines.

Fig. 2 is a plan view of Fig. 1 and 20 Fig. 3 is a fragmentary vertical section through a hollow furnace wall and supporting structure embodying my invention.

Referring to Fig. 3, I have here shown a 25 hollow wall construction such as used, for instance, in pulverized fuel furnaces comprising a refractory wall 7 relied on principally to withstand the intense heat within the furnace, and an outer structure or shell 8 relied on as the main element of structural strength for the wall. This outer wall 30 is composed of horizontal girder members A, which may be supported by upright buckstays (not shown) and a thermo-insulative layer 9, between the horizontal girders A, supported and held in position by the girders. 35

The inner wall 7 is supported or positioned by the outer wall to which end holding tile B are provided in the inner wall. The holding tile not only serve as a means 40 for dividing the space in the wall into horizontal compartments but also as a means for connecting the inner wall to the outer wall. The tile B are recessed as indicated in Figs. 1 and 2 so as to provide T shaped 45 openings 10 between adjacent tile extending the full thickness of the tile. Each one of the T shaped openings or reentrant recesses 10 is adapted to receive an end of one of the anchorage members C to be now described.

50 As best shown in Figs. 1 and 2 each anchor member C is of substantial T cross section with the head of the T adapted to interlock with the T openings or reentrant recess 10. The leg of the T has means for engaging

the support or girder A, such means in 55 this instance being a couple of inturned fingers 11 and 12 which interlock behind the corresponding girder flange. Horizontally the anchor C may be held fixed by engagement of the fingers 11 and 12 between portions of the thermo-insulative layer 9. The finger 11 extends well beyond the point of engagement with the girder A, thereby providing means for holding the anchor member firmly by the insulative layer 9 against longitudinal movement. The gap between the points 13 and 14 of the fingers is greater than the width of the flange 15 of the girder A. This permits of vertical movement of the member C so as to prevent any binding. A 70 certain amount of swinging movement may also be imparted to this member by virtue of the space 16 between the lower finger 12 and the flange 15, the upper finger fitting the flange relatively snugly in comparison. 75 Bosses 17 are provided on the web or leg portion of the anchor member to afford spot contact with the girder.

The head 18 of the anchor member has its 80 outside surface 19 curved both vertically and horizontally, and its inner surface 20 curved vertically and tapering toward the leg of said member. In other words the head may be said to bulge at its central portion, at which portion the brick contacts for rocking 85 movement both vertically and horizontally.

Since the inner wall is next to the zone 90 of combustion it obviously expands and contracts to a much greater extent than the outer shell. By virtue of the anchorage arrangement provided the inner wall is free to expand and contract with reference to the outer wall and this without imposing any great stresses on the holding tile, for the reason that the holding tile can rock both 95 horizontally and vertically with respect to the anchor, and the anchor itself can rock vertically on its supporting girder, as well as shift vertically bodily. The advantage of this will be appreciated when it is understood that if the holding tile should break off the entire wall would collapse.

100 The inner wall shields the metal from the heat and in addition the current of air which flows through the compartments of the wall 105 and passes into the furnace through the rows of openings 21 also serves to protect the metal against the heat.

The anchor members C owing to their simple design may be inexpensively made either as castings or forgings.

I claim:

5. 1. As a new article of manufacture, a brick anchoring member of substantial T section, the head being curved both vertically and horizontally for interlocking but rocking engagement in a reentrant recess in the member to be anchored, said anchoring member having means on the leg for engaging a support.

2. As a new article of manufacture, a brick anchoring member of substantial T section, 15 the head being of greater cross sectional area at its centre than at its extremities for interlocking but rocking engagement in a reentrant recess in the member to be anchored, and the leg of the T having means for engaging a support.

3. As a new article of manufacture, a brick anchoring member of substantial T section, the head being curved both vertically and horizontally for interlocking but rocking engagement in a reentrant recess in the member to be anchored and the leg having inturned fingers for engaging behind a support.

4. As a new article of manufacture, a brick anchoring member of substantial T section, 30 the head being curved vertically on its inside and outside surfaces for interlocking but rocking engagement in a reentrant recess in the member to be anchored, and the leg having inturned fingers for engaging behind the flange of a supporting girder.

5. As a new article of manufacture, a brick anchoring member of substantial T section, 40 the head being curved both vertically and horizontally for interlocking but rocking engagement in a reentrant recess in the member to be anchored, and the leg having inturned fingers for engaging behind the flange of a supporting girder, the greatest dimension 45 of the gap between the fingers being greater than the width of the girder flange.

6. As a new article of manufacture, a brick anchoring member of substantial T section,

the head being curved both vertically and horizontally for interlocking but rocking engagement in a reentrant recess in the member to be anchored and the leg having 50 inturned fingers for engaging behind a support, the upper finger extending well beyond the point of engagement with the girder. 55

7. As a new article of manufacture, a brick anchoring member of substantial T section, the head being adapted to interlockingly but rockingly engage in a recess in the member to be anchored, and the leg having in- 60 turned fingers for engaging behind a supporting girder, the upper of said fingers having relatively snug engagement with the girder flange and the lower being spaced from the girder flange to permit of swinging 65 movement of the member.

8. In an upright wall construction the combination of a girder, a wall, bricks of which are recessed, anchor members engaging the girder and each having a curved 70 portion forming a head interlocking in one of said recesses so as to permit vertical and horizontal rocking movement of the bricks.

9. In an upright wall construction the combination of a longitudinal girder, a wall 75 supported by said girder, a course of recessed tile of another wall adjacent the girder, and anchor members having means interlockingly engaging the girder but having freedom for limited vertical movement with 80 respect thereto, and having curved heads interlockingly but rockingly engaging in the recesses in the tile.

10. In an upright wall structure the combination of a support, refractories and intermediate anchoring means, said anchoring means having securing means engaging the support for movement with respect thereto, and the refractories and anchoring means having, respectively, recesses and curved 85 heads constructed to interlock in sliding and rocking engagement.

In testimony whereof, I have hereunto signed my name.

GEORGE P. JACKSON.
